UNITED STATES PATENT OFFICE.

ERNEST A. LEE, OF LORAIN, OHIO.

SEWING MACHINE.

Application filed April 14, 1921. Serial No. 461,206.

To all whom it may concern:

Be it known that I, ERNEST A. LEE, a citizen of the United States, and resident of Lorain, in the county of Lorain and 5 State of Ohio, have invented certain new and useful Improvements in Sewing Machines, of which the following is a specification.

This invention relates to sewing machines 10 and more particularly to sewing machines for closing bags in which the bags are carried along the machine by an endless conveyer.

The principal object of this invention is 15 to provide a sewing machine of this class having a conveyer for transferring the bags to be closed past the sewing head in either direction.

Another object is to provide a machine 20 of this class having a conveyer for handling the bags to be closed, in transferring them past the sewing head, and having means for running the sewing head when the conveyer is operated in one direction only.

25 Figure 1 is a front side elevation of a sewing machine, having my invention applied thereto.

Figure 2 is an enlarged detail of the clutch mechanism for controlling the operation of 30 the sewing head.

Figure 3 is a wiring diagram showing the control circuits to the operating motor of the machine.

Referring particularly to the drawings, 25 designates the supporting frame of the machine having a sewing head 3 supported thereon. Thread is fed to the sewing head 3 from suitable bobbins 4 supported on bracket 5 mounted to the rear of the sewing head.

A suitable endless conveyer 6, for conveying bags to be sewed, is mounted to travel over suitable rollers 7 and 7' journaled on shafts 8 and 8', respectively, projecting forwardly from the supporting frame 2. A roller support is mounted under the upper face of the conveyer 6 to prevent the conveyer sagging when the heavy bags are carried thereon, and comprises a frame 9 supported on brackets 10 and having rollers 11 journaled therein.

50 A reversing motor 12 is mounted beneath the frame 2 and is connected by a sprocket drive chain 12' to the roller 7' so as to drive the conveyer 6. A jack shaft 13 is journaled in the frame 2 and is geared to the

motor 12. A pulley 14 is mounted loosely on the shaft 13 and is connected by a belt 15 with the operating pulley 16 on the sewing head 3.

One member 17 of a toothed clutch is secured to the upper face of the pulley 14 and is adapted to be engaged by a co-operating clutch member 18, having co-operating teeth and slidably mounted on the shaft 13. 65 The clutch members 17 and 18 have ratchet-like teeth 19 on their engaging faces. That is, teeth that will hold in one direction of rotation only and are so arranged that they will hold only when the motor is operating 70 in the forward direction, that is in the direction necessary to move the conveyer from right to left in the direction of arrow X. It will, therefore, be apparent that since the same motor drives both the conveyer 6 and 75 jack shaft 13 the sewing head will operate only when the conveyer is operating in one (forward) direction.

A clutch lever 20 is pivotally supported 80 on a standard 21 secured to the sewing head 3 and is connected to the clutch member 18. A coil spring 22 has its one end secured to the sewing head 3 and its other end secured to the lever 20 so as to normally pull the lever 20 and clutch member 18 downwardly so that member 18 will be engaged 85 with the clutch member 17 on the pulley 14.

When the motor 12 is reversed the operator may pull down on the lever 20 to disengage the clutch members 17 and 18 and 90 thus prevent wear of the toothed faces, but whether the clutch members are disengaged or not the sewing head will not operate when the motor is reversed, as explained above.

The motor 12 is adapted to be controlled 95 by a foot or treadle switch 24 having insulated contacts 25 and 26 on each end, which contacts are in circuit with magnetic switches 27 and 28, respectively, each of 100 which has one up and one down contact. A resistance 29 is included in the motor circuit and a magnetic switch 31 is included in the circuit with the switches 27 and 28 and is adapted to cut out the resistance when the motor is running in the forward direction.

105 When the switch 24 is rocked to close contact 25 the circuit is closed from plus line through wire 32, contact 25, wire 33, through magnet coil of switch 27, through wires 34 and 47 to minus line, thus operating switch 27 closing the upper contact and opening the lower contact.

The shunt field 35 of motor 12 is connected across the line continuously by wires 36 and 37. The operation of the switch 27 closes the armature circuit to motor 12, as follows:—From plus line through wire 38 to top of switch 27 to wire 39 through armature A of motor 12, to wire 40, to switch 28, through the bottom contact of switch 28 and wire 41 to resistance 29 to wire 42, through series coils S of switch 31 and wire 43 to minus line.

When armature A has reached a predetermined speed, depending upon the adjustment of switch 31, this switch closes cutting out section B of resistance 29, thus connecting motor 12 directly across the line. A shunt coil 45 is employed to hold the switch 25 closed, since coil S is short circuited when the switch closes.

20 The above circuits are adapted to drive the motor 12 forward or in the direction necessary to operate both the conveyer and sewing head to close bags.

After a bag has been passed under the sewing head and it is desired for any reason to re-sew it, as for instance when one bag is enclosed within another and each bag is sewed separately, the operator will depress the opposite side of switch 24, closing contact 26 to reverse the motor 12.

35 The closing of contact 26 will make a circuit from the plus line through wire 32, contact 26, wire 46, through magnet coil of switch 28 and wire 47 to minus line, thus opening bottom contact of switch 28, and closing the armature circuit to motor in reverse direction from the plus line through wire 38, top contact of switch 28, wire 40, through armature and wire 39 to the bottom 40 contact of switch 27 through wire 49 and through section C of the resistance 29, through wire 42, coil S of switch 25, through wire 43 to minus line.

When the control switch 24 is in neutral 45 position with contacts 25 and 26 both open and armature A of the motor 12 is still revolving, dynamic braking for quickly bringing the armature to rest is obtained. The shunt field is constantly connected across the line as described above, and the armature is short circuited as follows—The bottom contact of switches 27 and 28 are held closed by a spring when the switch 24 is in neutral or off position—Circuit is then 50 made from one side of the armature A through wire 40, to bottom contact of switch 28, through wire 41 and sections B and C of resistance 29, through wire 49 to bottom

contact of switch 27, then through wire 39 and the opposite side of the armature A to 60 starting point.

The operation of this improved sewing machine is as follows:—The operator rocks the control switch 24 so as to close contact 25, thus making a circuit to the motor 12, 65 so as to operate the motor in the forward direction. That is, in the direction necessary to operate the conveyer 6 in the direction of the arrow X. The motor 12 also operates the sewing head 3, therefore when 70 a bag is placed on the conveyer 6 it is carried through the sewing head and sewed. When for any reason, as when double bags are used, it is desired to again sew the bag the operator will raise the lever 20 to disengage the clutch member 18 from the member 17, and rock the switch 24 to close contact 26 thus reversing the circuit to the motor 12 and causing the motor to operate 75 in the reverse direction, therefore operating the conveyer in the reverse direction, that is, in the direction of arrow Y, and carry the bag back to the starting point.

It will of course be understood that due to the clutch members 17 and 18 being disengaged, the sewing head remains inoperative during the reverse operation of the motor 12, although if the clutch members were not disengaged they would not operate the sewing head, due to the ratchet faces, 80 which are of ratchet tooth construction and are free to ride on each other in the reverse direction.

I claim:—

1. A bag sewing machine comprising a 95 sewing head, a conveyer for moving the bag past the head, means for operating said conveyer in opposite directions, and means for automatically rendering said sewing head inoperative when said conveyer is operated in 100 one direction.

2. A bag sewing machine comprising a sewing head, a conveyer for moving the bag past the head, means for operating said conveyer in forward and reverse directions, 105 said means including a reversing motor having a driving connection with said conveyer, and means for reversing said motor, a jack shaft geared to said motor and adapted to drive said sewing head, and a clutch for connecting said sewing head with said shaft, said clutch being operative only when motor is operating in a forward direction.

In testimony whereof, I have hereunto signed my name.

ERNEST A. LEE.
